F. C. WERBER

FLYER CONSTRUCTION FOR THREAD SPINNING AND TWISTING UNITS

Filed Dec. 13, 1926

Inventor
F. C. Werber,

By Clarence A. O'Brien.

Attorney

UNITED STATES PATENT OFFICE.

FRED C. WERBER, OF WILKES-BARRE, PENNSYLVANIA.

FLYER CONSTRUCTION FOR THREAD SPINNING AND TWISTING UNITS.

Application filed December 13, 1926. Serial No. 154,575.

This invention relates to a flyer construction for thread spinning and twisting units of the character shown and described in my Patent No. 1,569,831, granted to me on November 11, 1924, as well as in a copending application upon a spinning and twisting machine, Serial No. 154,577 filed December 13, 1926.

The primary object of this invention is to provide a rigidly balanced flyer wherein the same may be readily removed from or positively attached to the spindle of the spinning and twisting unit, and wherein the flyer thread receiving arm may be easily and rapidly detached from the flyer body to permit the renewal or repair of the same.

A still further object is to provide a device of this character wherein the body attaching end of said thread receiving arm is so formed with respect to the body as to become securely locked thereto as soon as properly associated therewith, and this without requiring any outside agency.

The invention further aims to provide a flyer including a single thread receiving arm having balancing means in opposed relation with the arm so that there will be absolutely no vibration of the spinning and twisting unit spindle especially at high speeds thereof.

A further salient object is to provide a readily detachable thread guide eye for the thread receiving end of the flyer arm so that the same may be renewed when necessary.

Other objects will become apparent as the nature of the invention is better understood, the same comprising the novel form, combination and arrangement of parts hereinafter more fully described, shown in the accompanying drawing and claimed.

In the drawing wherein there is disclosed two embodiments of the invention,

Figure 1 is a fragmentary view partly in section and partly in elevation of a thread spinning and twisting unit as fully shown and described in my said patent and copending application, the spindle thereof being equipped with a flyer constructed in accordance with the present invention.

Figure 2 is an enlarged longitudinal section taken substantially upon the line 2—2 of Figure 1.

Figure 3 is a section taken at right angles through the device as disclosed in Figure 2.

Figure 4 is an inner side elevation of the flyer.

Figure 5 is an inner side elevation of a slightly modified form of the invention, and

Figure 6 is a longitudinal section therethrough.

First having reference to Figures 1 to 4 inclusive, the spindle of the spinning and twisting unit is designated A, while the form of the improved flyer shown in these figures is designated generally by the reference character B. This flyer consists of a circular steel plate 5 having an opening 6 at its center from which projects a collar 7 for providing a wide supporting surface 70 for the plate when the same is disposed upon the spindle A, see Figure 3. The outer edge of this plate is formed with a circumferential flange 8 concentric with the sleeve 7 and of a width substantially equivalent 75 thereto.

Said flange 8 is formed with an opening 9 through which a radial thread guide arm 10 passes, which arm is in the form of a length of steel wire as indicated in the drawing. The inner end of this wire is so bent as at 11 to engage around the major portion of the collar 7, while the extreme end of the wire is bent laterally outwardly to provide a locking pin 12, that is to be forcibly engaged within a slot 13 of said flange 8. The slot 13 is spaced about ninety degrees from the flange opening 9, while the curved portion 11 of the wire normally tends to expand away from the collar with 90 the result that the pin 12 is frictionally held within the slot in an obvious manner. However, the wire may be readily removed from the spindle attaching plate 5 by forcibly releasing the pin from the slot and then 95 threading the end of the wire through the flange opening 9.

The extreme outer end of the wire is so bent upon itself as to provide a relatively oval shaped longitudinal eye 14. This eye 100 is normally closed by reason of the end of the bent over portion of the wire, which partially forms said eye, being bent past the wire arm proper as clearly disclosed in Figures 1 and 4. This eye 14 is provided 105 for the purpose of permitting of the rapid attachment of a relatively small porcelain sleeve 15 through which the thread from the spindle A is extended as indicated in Figure 1. By reason of this porcelain sleeve, the 110

thread does not come into contact with the wire arm which would otherwise result in the weakening and cutting of the thread. Obviously, when it is desired to remove this 5 thread guide sleeve, it is only necessary to forcibly pull downwardly upon the same for springing the outer portion of the eye away from the flyer wire proper. On the other hand, one of these guide sleeves may be 10 readily associated with the eye by merely placing the same upon the end member of the eye and then forcing upwardly thereon. As soon as the sleeve is associated with the 15 wire eye as indicated in Figures 1 and 4, this eye will assume the locking position disclosed in said figures.

For counterbalancing the weight of the flyer arm, there is disposed between the flange 8 and collar 7 in opposed relation 20 with the opening 9 in said flange 8, a weight 16 preferably in the form of a rectangular block of metal that is formed centrally with a threaded opening that will register with an opening in the collar 7 and an enlarged 25 opening in the flange 8 when said weight is disposed between the flange and collar as more clearly disclosed in Figure 3. For securing this weight to the flyer and for providing means of attachment of the flyer to 30 the spindle A, a screw 17 is threaded into the opening of the weight, the inner end of the screw being engaged within the opening of the collar 7 so that the screw may be forced into engagement with the spindle for 35 locking the flyer thereon. Obviously, the large opening in the flange 8 permits access to the headed end of the screw so that the same may be turned by a screw driver.

In the form of the invention disclosed in 40 Figures 5 and 6, the same consists of a relatively large sheet metal plate 5' flanged circumferentially at its edge as at 8'. The center of this plate 5' is formed with an opening for receiving one end of a sleeve 7' 45 that is formed inwardly of the end engageable through the opening in the plate with a circular flange 18, the inner face of which is forced into engagement with the plate 5' after which the end of the sleeve projecting 50 through the opening is turned over to rigidly connect the sleeve to said plate, see Figure 6.

The flange 8' of this flyer plate 5' is formed with an opening 19 through which is 55 extended the wire flyer arm 20, the inner end of which is bent into circular formation for engagement within a circumferential channel of the sleeve 7' formed by rabbeting the periphery of the flange 18 thereof. The extreme inner end of this wire arm is formed 60 with a hook 21 for engagement with the wire arm proper as indicated more clearly in Figure 5 so as to prevent the expansion of the ring-like end of the flyer arm and its consequent disengagement from the sleeve 65 7', which sleeve carries a set screw 22 for

the purpose of permitting of the rigid attachment of the flyer to the spinning and twisting unit spindle.

In opposed relation with the opening 19 of the plate flange 8' through which the wire 7' arm 20 passes and at opposite sides thereof the said plate 5' is formed with a pair of struck out tongues 23-23 for the purpose of permitting of the attachment of a flyer arm counterbalancing weight 24 thereto, 7' which weight is in the form of a length of wire preferably of lead or other weight material.

It will thus be seen that I have provided two forms of flyer construction, each of 8 which is well adapted for all the purposes heretofore designated, and even though I have herein shown and described these forms of the invention as consisting of certain detail structural elements it is nevertheless to 8 be understood that some changes may be made therein without effecting the spirit and scope of the appended claims.

Having thus described the invention, what I claim as new and desire to secure by Letters Patent is:—

1. In a flyer for thread spinning and twisting units, a member constructed for rigid attachment to the unit spindle and having a lateral, apertured flange, an arm 9 extending through said flange aperture and radially from said member and a counterbalancing weight associated with the member in opposed relation with respect to the arm.

2. In a flyer for thread spinning and twisting units, a member constructed for rigid attachment to the unit spindle and having a lateral, apertured flange, and an arm extending through said flange aperture 1 and radially from said member and having its inner portion detachably connected with the member.

3. In a flyer for thread spinning and twisting units, an apertured member constructed for rigid attachment to the unit spindle, an arm extending through and radially from said apertured member and readily detachably connected therewith, and a counterbalancing weight associated with 1 the member in opposed relation with respect to the arm.

4. In a flyer for thread spinning and twisting units, a member constructed for rigid attachment to the unit spindle, an arm 1 extending radially from said member and readily detachably associated therewith, a counterbalancing weight associated with the member in opposed relation with respect to the arm, and a single member for facilitating the attachment of the counterbalancing weight to said first mentioned member, and for the securing of said member to the unit spindle.

5. In a flyer for thread spinning and

twisting units, a circular body having an opening in the center thereof to permit the disposition of the body upon the unit spindle, a collar upon the inner side of the body and coaxial with said opening, an arm extending radially from the said body and being so bent at its inner end as to engage around said collar and a counterbalancing weight associated with the body in opposed relation with said arm.

6. In a flyer for thread spinning and twisting units, a circular body having an opening in the center thereof to permit the disposition of the body upon the unit spindle, a collar upon the inner side of the body and coaxial with said opening, an arm extending radially from the said body and being so bent at its inner end as to engage around said collar and a counterbalancing weight associated with the body in opposed relation with said arm, and a single member for securing the counterbalancing weight to the body and said body to said unit spindle.

7. In a flyer for thread spinning and twisting units, a member constructed for rigid attachment to the unit spindle, an arm extending radially from said member and formed at its outer end with an eye having a free end portion and a thread guide sleeve removably arranged on said end portion of the eye of said arm.

8. In a flyer and in combination, a member having an inner portion and also having a flange, an arm extending from the flange of

the member and engaged with said flange 35 and detachably connected with the inner portion of the member, and a counterbalance weight carried by the member within the flange thereof.

9. In a flyer, and in combination, an arm 40 having at its outer end an eye and also having a free end portion normally maintained by the inherent resiliency of the arm against the major portion of the arm, and a thread guide sleeve removably arranged on said end 45 portion of said eye.

10. In a flyer, and in combination, a member, an arm carried by and extending from the member and having an eye, and a thread guide arranged on and receiving a portion 50 of said eye.

11. In a flyer, and in combination, an arm having an eye, and a thread guide sleeve removably arranged on and receiving a portion 55 of the arm forming said eye.

12. In a flyer and in combination, a member having an inner portion and also having a flange surrounding and spaced from said inner portion, and an arm extending from and engaged with the flange of the member and detachably connected with the inner portion of the member, said arm extending in a substantially radial direction through the space between the inner portion of the member and the flange thereof.

In testimony whereof I affix my signature.

FRED C. WERBER.
